Atty.

UNITED STATES PATENT OFFICE

FREDERICK GEORGE SCHRANZ, OF PHILADELPHIA, PENNSYLVANIA, ASSIGNOR TO
SOUTHWARK FOUNDRY & MACHINE COMPANY, OF PHILADELPHIA, PENNSYLVANIA,
A CORPORATION OF PENNSYLVANIA

STEAM PLATEN

Application filed August 21, 1929. Serial No. 387,337.

My invention relates to steam plates or as they are called "platens", such as employed in the curing, vulcanizing, or other heat treatment of rubber and composition goods, synthetic resins, bakelite, etc., or for other purposes where a heated plate is required; such plates or platens having internal passages for the circulation of steam or other heating media and in some instances cooling media; 5 in other words "temperature-controlling" media. For such purpose provision is made for the introduction and withdrawal of such temperature-controlling media and in order to provide for circulation throughout the 10 whole extent of the plate or platen, the passages therein are in communication with each other and provide a continuous conduit.

The present invention comprises a plate or platen having a series of cross passages placed relatively close together and extending in one direction with respect to the marginal edges of the platen; such cross passages being suitably connected by short passages formed in the walls between pairs of said 20 passages alternately adjacent opposite edges of the plate or platen, with a continuous passage formed by a tube (or tubes) introduced into a bore (or bores) of the platen which may be located adjacent an edge or margin 25 of the same (or both edges) and disposed at right angles to said cross passages.

The passage or space formed by the tubular member (or members) is open to cross passages at opposite ends of the plate or platen and provides a straight section of the conduit adjacent one side of the plate. The passage just described provides a conduit of material length which may be employed for the inlet or return of the temperature controlling media. If the tube forms a part of the return passage just prior to discharge of the temperature controlling media the latter will be retained for a longer period than with the usual forms of platens. The tube forming 30 the continuous passage at right angles to the

cross passages may be of non-ferrous metal and is placed in the bore receiving the same by a force fit. The cross passages are connected alternately at their ends by short passages which may be formed by burning the 50 wall of metal between pairs of passages adjacent to the edges of the platen in the manner set forth in the patent of H. J. Ruch, No. 1,594,121.

These and other features of my invention 55 are more fully described hereinafter; reference being had to the accompanying drawings, in which:

Figure 1 is a plan view of a steam plate or platen having an internal channel or conduit formed in accordance with my present invention; such view being partly in section.

Fig. 2 is an edge view looking in the direction of the arrow *a*, Fig. 1.

Fig. 3 is an edge view looking in the direction of the arrow *b*, Fig. 1, and

Fig. 4 is an enlarged sectional view of a portion of the platen shown in Fig. 1.

In the drawings, 1 represents the body of the plate or platen which is preferably of 70 rolled steel and of uniform thickness throughout its entire extent. It is desirable in the manufacture of these plates that the faces be absolutely parallel, and for some uses, it is desirable to grind and polish the surfaces 75 after they have been developed into the true planes desired.

The plate may be rectangular in contour and in the drawing (for illustrative purposes only) it is indicated as being slightly longer 80 than wide; the marginal sides or edges indicated at *A* and *B* being somewhat longer than the marginal sides or edges indicated at *C* and *D*. This shape, however, is not representative of all plates embodying this invention and the invention is not to be limited to any dimensions of either width or length relatively to each other, as square plates or plates of other dimensions may include the features 85 of the present invention.

For the purpose of description only, the marginal edges indicated at A and B may represent the "length" of the plate and the marginal edges indicated at C and D may represent the "width" of the plate. The plate may be bored or drilled from side to side of the same or between the marginal edges A and B to form cross passages 2, 2^a, 2^b, 2^c, et seq.

10 In order to provide communication between adjacent cross passages, the metal wall between the same may be cut in the manner set forth in the Ruch patent before referred to. These short connecting passages, indicated at 3, are disposed adjacent opposite edges of the plate, alternately arranged, and provide with the cross and other passages the continuous conduit for the circulation of heating or cooling media.

20 Adjacent one end of the plate, shown in the present instance as that indicated at D at the right, a short cross passage 2¹ enters the plate from the side or edge B and terminates short of the longitudinal axis of the plate; such passage communicating with a short passage 4 extending to the edge D. In line with this passage 2¹ is a passage 2^m which enters the plate from the marginal edge A and terminates short of the longitudinal axis of the plate; such passage communicating with a short passage 5, also extending to the edge D. A pipe 4^a for the inlet of steam or other temperature controlling media is connected to the short passage 4 extending longitudinally of the plate and in communication with the passage 2¹, while a pipe 5^a is connected to the short longitudinal passage 5 in communication with the passage 2^m for the discharge of steam or other temperature controlling media after circulation through the conduit formed by the several bores or passages of the plate. If desired these connections may be reversed and the pipe 5^a employed for the inlet of the temperature controlling media and the pipe 4^a for the exhaust.

30 In the present instance the outlet for the steam or other temperature controlling media is disposed adjacent to the inlet therefor. Under some circumstances it may be desirable to retain the temperature controlling media within the conduit of the platen for a greater length of time than is possible if, for instance, the steam or other temperature controlling media entered at one corner of the plate and was discharged at the opposite corner thereof. In the present arrangement, after the steam or other temperature controlling media has entered the 40 final cross passage 2 indicated at the left of the plate it passes therefrom to the tubular member and from the latter to the short cross passage 2^m, passage 5, and thence to the exhaust pipe 5^a.

45 At one side of the platen, shown in the

present instance as adjacent the marginal edge A, a bore 6 is provided, which may extend from end to end of the platen; such bore cutting across each of the cross passages 2, 2^a, 2^b, 2^c, et seq. Within this bore, a thin-walled tube 7 is introduced, which may be of a non-ferrous metal, and for such purpose a brass tube may be employed. To afford communication between this tube and the end cross passages, that indicated at 2 at the left of the plate and the short passage indicated at 2^m at the right of the plate, for instance, the tube is drilled through as indicated at 7^a, in line with such passages. This drilling operation may take place before or after the tube 7 has been forced to its seat. And as may be readily noted, the tube forms a continuous passage along one side of the platen between the passage indicated at 2 at the left of the plate and a passage indicated at 2^m.

50 The passage 6 receiving the tube 7 may have its end closed by screw plugs 10, and elastic washers 7^b may be placed between the inner ends of said screw plugs and the ends of the tube 7. The passage 2 at the left of the platen may have its open ends closed by suitable means, screw plugs 10^a being indicated in the present instance. The open ends of the several cross passages 2, 2^a, 2^b, 2^c, et seq., may be closed by suitable plugs 10^b, which may be threaded or welded in place, or secured in any other approved manner that will insure a fluid-tight joint with the body of the plate.

55 While the cross passages 2, 2^a, 2^b, 2^c, et seq., are shown as extending entirely through the plate from edge to edge, it is obvious that certain of these passages might stop short of the marginal edge of the plate and be connected to an adjacent passage by 60 burned apertures 3, without departing from my invention.

65 It is desirable that the marginal edges of the plate shall be entirely smooth and that all plugs closing the ends of the several cross passages shall be flush with such sides or ground down so as to make them flush to insure that such screw plugs will not offer any roughness in the form of burrs or projections at their edges. In the case of the screw plugs indicated at 10 and 10^a their outer surface may be rounded as clearly indicated in Fig. 4; and such outer and curved surfaces of these plugs may lie wholly within the recess receiving the same and below the plane of the surface of that portion of the edge in which they are placed.

70 The upper and lower surfaces of the plate may have their longitudinal edges on opposite faces slightly reduced, as indicated at 11 and 12, Fig. 3; such reduced portions insuring that no edge mars or fins will affect the desired plane surfaces which extend over sub-

stantially the entire area of the platen, parallel with each other.

The edges of the plates may be tapped as indicated at 13 for the mounting of guide brackets, supports or attachments when assembling the plates in a press.

I claim:

1. A heating platen comprising a thin-walled plate of metal having a plurality of drilled passages extending in one direction with respect to opposite marginal edges of the same; said plate having apertures connecting alternate pairs of passages at opposite sides of the plate, with alined cross passages at one edge of the plate less than the full dimensions of the plate, inlet and exhaust connections at one end of the plate disposed at right angles to said shorter cross passages, and closures for the ends of said several passages.

2. A heating platen comprising a thin-walled plate of metal having a plurality of drilled passages extending in one direction with respect to opposite marginal edges of the same; said plate having apertures connecting alternate pairs of said passages at opposite sides of the plate and a bore adjacent one edge of the plate at right angles to said passages and cutting through the same, inlet and exhaust connections communicating with said passages, a tubular member fitting within said bore and in communication only with cross passages at the ends of the plate, and closures for the ends of said several passages.

3. A heating platen comprising a thin-walled plate of metal having a plurality of drilled passages extending in one direction with respect to opposite marginal edges of the same and including short passages terminating intermediate said marginal edges; said plate having apertures connecting alternate pairs of said passages at opposite sides of the plate and a bore adjacent one edge of the plate at right angles to said passages and cutting across the same, a tubular member fitting within said bore and in communication only with cross passages at opposite ends of the plate, closures for the ends of said several passages, and inlet and exhaust connections communicating with said shorter passages.

4. A heating platen comprising a thin-walled plate of metal having a plurality of horizontal bores forming passages extending in one direction with respect to opposite marginal edges of said plate; the latter having apertures connecting alternate pairs of passages at opposite sides of the plate and a bore adjacent one edge of the plate at right angles to said passages and cutting through the same, with alined cross passages at one edge of the plate less than the full dimensions of the plate, inlet and exhaust connections at right angles to said shorter cross

passages substantially midway opposite edges of the plate, a tubular member fitting within said bore and in communication only with cross passages at the ends of the plate, and closures for the ends of said several passages.

5. A heating platen comprising a thin-walled plate of metal having a plurality of parallel passages extending in one direction with respect to opposite marginal edges of the plate; the latter having connections between alternate pairs of passages to form a continuous conduit and a bore at one edge of the plate at right angles to said passages and cutting through the same, with alined cross passages at one end or edge of the plate less than the full dimensions of the plate and connections therefor at right angles thereto substantially midway opposite edges of the plate, a tubular member of a metal differing from that of the plate fitting within said bore and in communication only with passages at the end of the plate, and closures for the ends of said several passages.

6. A heating platen comprising a thin-walled rectangular plate of metal having a plurality of horizontal bores forming parallel passages extending in one direction with respect to opposite marginal edges of the plate; with alined cross passages at one end or edge of the plate less than the full dimensions of the plate and connections therefor at right angles thereto substantially midway opposite edges of the plate for the inlet and exhaust of temperature controlling media and a bore at one edge of the plate at right angles to said cross passages and cutting through the same, a tubular member fitting within said bore and in communication only with passages at the end of the plate, screw plugs having rounded heads closing the ends of the bore receiving said tube, and closures for the ends of said several cross passages.

7. A heating platen comprising a thin-walled plate of metal having a series of cross passages in parallel relation; pairs of said passages being in communication with each other by short cross passages adjacent opposite edges of the plate to form a continuous conduit, inlet and exhaust connections for said conduit, a continuous return passage communicating with the exhaust and disposed at one side of the platen at right angles to the cross passages; said return passage extending the full length of the platen and being in communication only with the cross passages at opposite ends of the platen, and closures for the ends of the several passages.

8. A heating platen comprising a thin-walled rectangular plate of metal having a series of cross passages in parallel relation; pairs of said passages communicating with each other by short cross passages adjacent opposite edges of the plate to form a continuous conduit, inlet and exhaust connections for said conduit arranged side by side,
